UNITED STATES PATENT OFFICE.

OSWALD J. NEFF, OF EASTON, PENNSYLVANIA.

WINDOW ATTACHMENT.

1,380,237.

Specification of Letters Patent. Patented May 31, 1921.

Application filed June 11, 1920. Serial No. 388,269.

To all whom it may concern:

Be it known that I, OSWALD J. NEFF, a citizen of the United States, residing at Easton, in the county of Northampton and 5 State of Pennsylvania, have invented new and useful Improvements in Window Attachments, of which the following is a specification.

The present invention has reference to an 10 attachment for windows.

The object of the invention is to produce a device which may be easily secured to a window casing to project outwardly therefrom, the said device having transparent 15 panels whereby the occupant of a room may observe surroundings both in front and to the sides of the room.

It is a further object of the invention to produce a removable collapsible bay window 20 attachment for ordinary window casings which may be either square, oblong or any other desired shape, which may be easily and securely attached to the window casing or frame and as readily removed therefrom, 25 and which, when not desired for use may be folded to provide a small bundle or package for storage or transportation.

The foregoing objects, and others which will appear as the nature of the invention 30 is better understood, may be accomplished by a construction, combination and operative arrangement of parts such as is disclosed by the drawings,

In the drawings:—

35 Figure 1 is a perspective view illustrating one form of the improvement.

Fig. 2 is a similar view showing a second form of the improvement.

Fig. 3 is a horizontal sectional view approxi- 40 mately on the line 3—3 of Fig. 1.

Fig. 4 is a similar sectional view approxi- 45 mately on the line 4—4 of Fig. 2.

Fig. 5 is a vertical transverse sectional view approximately on the line 5—5 of Fig. 1.

Fig. 6 is a perspective view of the top member, looking toward the under face thereof.

Fig. 7 is a view showing the improvement 50 folded.

In Fig. 1 of the drawings my improved bay window attachment for ordinary windows presents a front, sides, and angle corners between the front and sides, while in 55 Fig. 2 the improvement employs a straight front and right angular sides. The im-

provement is susceptible to many other forms of construction, it being understood that the size and shape of the device may be varied to accord with the suggestions or 60 requirements of the user.

Referring now particularly to the preferred embodiment of the invention illustrated in perspective Fig. 1, a window casing of the ordinary construction is indicated 65 by the numeral 1. To the sides of the casing, outward of the sashes is secured my improvement which is broadly indicated by the numeral 2. The improvement has its body constructed of a plurality of sections, all of 70 which being hingedly connected whereby the sections may be folded against each other when the device is not in use. The front includes a central mullion 3 to which the glazed frames or panels 4 are hinged 75 as at 5. The mullion 3 comprises a channeled member which is substantially U-shaped in cross section and which has its outer edges formed with oppositely extending flanges which are indicated by the nu- 80 meral 6, and to these flanges the hinges 5 for the panels 4 are secured. The channeled face of the mullion is arranged upon the outer face of the improvement, as the sides, hereinafter to be referred to, are 85 usually of a greater width than the respective panels 4, and therefore when the sides are swung over the panels 4, and the panels are swung to a right angle on the mullion the free and outer ends of the sides will be 90 received in the channel of the mullion.

It should be here stated that the joints between all of the hinged parts of my improvement are protected by weather excluding strips 7.

95 The outer edges of the panels 4 are beveled and the confronting edges of the corner panels 8 are likewise beveled. By this arrangement the corner panels may be retained at a desired angle with respect to the 100 front panels. The corner panels are glazed and are hingedly connected to the front panels as indicated by the numeral 9. To the corner panels the side panels 10 are hinged as at 11. The side panels may be 105 also glazed, and the confronting edges of both of the corner and side panels are beveled as indicated by the numerals 12 and 13 respectively.

110 Preferably, but not necessarily the panels of the improvement, at the adjacent or lower edges thereof are provided with inwardly

extending cleats indicated by the numeral 14, and to these cleats the bottom board 15 of the improvement is secured. The said board may be secured to the cleats in a manner which will permit of the removal of the bottom board when desired. As a matter of fact the bottom board may be dispensed with and a screen or the like may be substituted therefor.

10 The side panels, adjacent their inner ends have openings therethrough, and through these openings pass the securing elements 16 which enter the sides of the window casing. The securing elements are preferably in the 15 nature of screws which are readily inserted and readily removed.

The top or roof of the construction is indicated by the numeral 17. This roof is in the nature of a flat member and has on its 20 under face depending cleats arranged in spaced pairs, the outer cleats being indicated by the numeral 18 and the inner cleats by the numeral 19. Between these cleats the upper edges of the body portion of the device 25 are received, and if desired securing elements, such as short brads may be passed through the inner cleats 19 to engage with the body members of the construction. The roof has at its inner edge an upturned flange 30 20, and this flange, adjacent to the ends thereof has openings therethrough for the reception of securing elements that enter the side members of the window casing.

The improvement may be easily and 35 quickly set up upon a window casing and when employed the occupant of a room may readily observe conditions on the exterior thereof to either side of the room which is not possible with an ordinary straight window. In addition to this the improvement, 40 when a reticulated floor is employed therefor, serves as a ventilator for cooling the air in the window.

The construction illustrated in the modification disclosed in Fig. 2 and in the sectional views has the front thereof constructed in the same manner as that previously described, but the corner panels are dispensed with and the side panels 21 are hingedly connected to the front panels 22. 45 The front panels are hinged as at 23 to a central piece in the nature of a channeled mullion 24 that is similar to the mullion 3. The top 25 is of the same construction as the top or roof 17, except that the depending 50 cleats 26 and 27 which are arranged in spaced pairs on the under face thereof are shaped to receive therein the right angularly arranged front and sides.

It is believed that the simplicity of the construction and the advantages thereof will present themselves to those skilled in the art to which such inventions appertain without further detailed description.

Having thus described the invention, what 65 I claim is:—

A collapsible and removable bay window attachment for window casings, comprising a plurality of hingedly connected transparent panels, a channeled mullion between the 70 front panels to which the said front panels are hinged, the channel of the said mullion being designed to receive therein the edges of the outer panels when the latter are folded upon the front panels and the front 75 panels are folded against the sides of the mullion, cleats on the inner face of the panels adjacent to the lower edges thereof, a bottom secured to the cleats, a top having depending spaced cleats receiving therebetween the upper edges of the panels, securing 80 means for the top, and weather excluding strips at the confronting hinged ends of the panels.

In testimony whereof I affix my signature. 85
OSWALD J. NEFF.
